UNITED STATES PATENT OFFICE.

FRANK A. GOELZ, OF KEYPORT, NEW JERSEY.

CONVERTIBLE CHAIR.

1,193,257.

Specification of Letters Patent. Patented Aug. 1, 1916.

Application filed January 18, 1916. Serial No. 72,786.

To all whom it may concern:

Be it known that I, FRANK A. GOELZ, a citizen of the United States, residing at Keyport, in the county of Monmouth, State 5 of New Jersey, have invented certain new and useful Improvements in Convertible Chairs; and I do hereby declare the following to be a full, clear, and exact description of the invention, such as will enable others 10 skilled in the art to which it appertains to make and use the same.

The present invention is directed to improvements to convertible chairs and more particularly to one which can be converted 15 into several useful articles of furniture, such as a couch, stretcher or dressing stand.

The invention has for its object to provide a chair of this nature which can be quickly adjusted for different purposes.

20 A further object of the invention is to provide a chair of this nature having compartments for storing tools or other small articles, as well as wearing apparel.

A still further object of the invention is 25 to provide novel means for holding the legs of the chair in their operative or inoperative position.

With these and other objects in view, this 30 invention resides in the novel features of construction, formation, combination and arrangement of parts to be hereinafter more fully described, claimed and illustrated in the accompanying drawing, in which:—

Figure 1 is a perspective view of the chair 35 when used as a reclining chair. Fig. 2 is a longitudinal sectional view therethrough. Fig. 3 is a side elevation; showing the chair in use as a couch. Fig. 4 is a bottom plan view thereof. Fig. 5 is a side elevation of 40 the chair, showing the table extended when the chair is used as a dressing stand. Fig. 6 is a top plan view of the chair shown in Fig. 5, and with the seat raised to better illustrate the compartments. Fig. 7 is a 45 bottom plan view of the chair when the legs are folded. Fig. 8 is a rear view of the chair when the table is extended. Fig. 9 is a fragmentary view of the door.

The chair comprises a body 1 which is 50 rectangular in shape and has pivotally connected to the sides 2 thereof, the lower ends of the bars 3, said bars having attached thereto the back 4. Pivotally connected to the bars are the arms 5 which are connected 55 by a bar 6, said bar being adapted to selectively engage the notches 7 formed in the

upper edges of the sides 2 of the body 1, whereby the back 4 may be supported in different adjusted positions.

Pivotally connected adjacent the forward 60 ends of the sides 2 are bars 8, said bars having their upper ends pivotally connected to the bars 3 by arms 9. Thus it will be seen that when the back 4 is adjusted the bars 8 will be rocked, said bars being connected 65 by a strip 10.

A foot rest 11 is provided and has fixed thereto a shaft 12, which has its ends journaled in the lower ends of the bars 8, said shaft being provided with clamping nuts 70 13, whereby the foot rest may be held in different adjusted positions.

Fixed transversely of the body 1 is a strip 14 to which is hingedly connected the rear 75 edge of the seat 15 which normally closes the forward end of the body 1, said seat being common to the compartments 16 which are formed by the partitions 17, said compartments serving to receive articles.

It will be noted that the rearmost partition 17 so divides the body as to provide a comparatively large compartment 18 which may be used for storing articles of any description.

A table 19 is provided and is adapted to 80 slide on the ledges 20 formed on the sides of the body, said table when in its inoperative position serves to close the compartment 18. When the table is extended for use, the frame 21 is swung downwardly so 85 as to support the rear end of the table, said frame being formed from a single piece of metal bent so as to provide side arms 22 which have their upper ends bent inwardly to provide extensions 23, said extensions being hingedly connected to the plates 24 which are fixed to the table. The lower ends of the arms 22 terminate in coils 25 which constitute feet, said coils being connected by the cross bar 26.

The arms are provided with eyes 27 which have attached thereto the links 28, said links being adapted to have their free ends detachably engage the pins 29 carried by the 90 sides of the table 19, and when engaged thus, the frame 21 will be properly braced to sustain the weight of the table 19. It is obvious that the frame can be folded upon the upper surface of the table when the table is not in use and as clearly shown in Fig. 110 1 of the drawing.

Legs 30 are provided and have one of

their ends pivotally connected to the sides 2 of the body, said legs having supported in their free ends the ends of the axles 31 on the outer ends of which are mounted rollers 32, or if desired the legs may be equipped with casters.

10. Mounted adjacent each corner of the bottom 33 of the body are guides 34 in which are slidably mounted bars 35, the outer ends of which being provided with handles 36. It will be noted that when the bars 35 are in their extended positions, they are engaged by the legs 30, thus holding the legs in their operative positions, but when the 15 bars are withdrawn the legs can be swung upwardly. This is only necessary when the device is to be used as a stretcher and at which time the same can be conveniently carried from place to place.
20. The inner ends of the bars 35 are connected by bars 37, whereby each pair of bars 35 can be simultaneously slid into their operative or inoperative position, and to hold the bars 35 in their operative position 25 a pair of latch bars 38 is pivotally connected to the bottom whereby said bars can be rotated so that their ends will engage the bars 37, thus holding the bars 35 positively in their extended positions.
30. To one of the bars 37 is pivotally connected a latch 39 which is adapted to engage a keeper 40 on the adjacent bar, whereby the bars 35 may be held in their withdrawn or inoperative position. To the back 4 is 35 hingedly connected a door 41, which has attached thereto a mirror 42 which may be secured in any suitable manner.
- From the foregoing description it will be 40 seen that a chair has been provided which can be easily and quickly adjusted for different purposes, and one which provides means for storing articles of different de-

scription, such as tools or articles of wearing apparel.

The door 41 has its inner surface provided 45 with a plurality of straps 42' which are adapted to hold tools and the like; and as shown in Fig. 9.

While the device as illustrated is formed from suitable wood, it is obvious that the 50 same can be made from sheet metal if desired, and since the legs 30 can be folded as well as the arms 9 and bars 8 the chair, when folded can be stored within a very small space. 55

What is claimed is:—

1. A chair of the class described, comprising a body, legs pivotally connected to the sides of the body, bars slidably engaged with the bottom of the body for engaging the legs 60 to hold the same in their operative positions, and pivoted latch bars carried by the bottom for engaging the bars, as and for the purpose set forth.

2. A chair of the class described, comprising a body, guides mounted on the bottom of the body, bars slidably engaged in the guides, spaced bars having their ends engaged with the ends of said bars, latch bars pivotally connected to the body and between the second named bars and adapted to have their ends engage therewith for holding the first named bars in their extended positions, legs pivotally connected to the sides of the body and adapted to engage the 70 extended ends of the bars, whereby said legs are held in inclined positions to hold the body in an elevated position. 75

In testimony whereof, I affix my signature, in the presence of two witnesses.

FRANK A. GOELZ.
